Primary Examiner — Darlington Ly*(74) Attorney, Agent, or Firm* — Neal Gerber & Eisenberg LLP(57) **CLAIM**

The ornamental design for an attachment for suction device, as shown and described.

DESCRIPTION

1. Attachment for suction device

1.1 is a first perspective view of an attachment for suction device embodying our new design.

1.2 is a second perspective view thereof, with an outer sleeve removed to show a threaded surface.
